BLOCK-SIGNALING AND STOPPING SYSTEM.

1,257,961.

Specification of Letters Patent. Patented Feb. 26, 1918.

Application filed July 31, 1915, Serial No. 42,860. Renewed January 21, 1918. Serial No. 213,101.

To all whom it may concern:

Be it known that I, FRANK C. WILLIAMS, a citizen of the United States, and a resident of Philadelphia, county of Philadelphia, and State of Pennsylvania, have invented certain new and useful Improvements in Block-Signaling and Stopping Systems, of which the following is a specification.

10 The main objects of this invention are to provide in a block signal and stopping system for railways improved automatic stopping mechanism adapted to be carried by a car or train; to provide an improved combination of electrical circuits and devices for actuating automatic stopping mechanism; and to provide other improvements as will appear hereinafter.

In the accompanying drawing the figure 20 is a fragmentary view of a block signal and stopping system constructed in accordance with this invention.

Referring to the drawing, one embodiment of this invention comprises a railroad 25 track including two parallel rails 1 and 2, which, for controlling signals, are divided by staggered pairs of insulations 3 and 4, 5 and 6, and 7 and 8, into a plurality of blocks A, B—B, C—C, and D; block A extending from a point upon the left (not shown) to the first pair of insulations 3 and 4; block B—B extending from the latter insulations to the pair 5 and 6 upon the right; block C extending from the last-mentioned pair to the pair 7 and 8 upon the extreme right of the drawing, and block D extending toward the right from the last-mentioned pair.

For automatically stopping trains, the 40 rails 1 and 2 are subdivided in each block by two pairs of staggered insulations 9 and 10, and 11 and 12, dividing each block into what may be appropriately termed train stopping rail sections 9—11 and 10—12, and 45 block signal rail sections (for instance block signal rail sections 3—9, 4—10, 11—5, and 12—6 of block B—B, and block signal rail sections 5—9, 6—10, 11—7, and 12—8 of block C—C). The train stopping rail sections 9—11 and 10—12, are interposed in 50 each block between the corresponding block signal rail sections and the block signal rail sections of each block are electrically connected respectively by wires 15 and 16.

55 Each of the blocks A, B, C and D is pro-

vided with a block signal 20, which may be controlled in any suitable manner by track circuits, including the block signal rail sections, or may be controlled in any other manner. In the drawings only two of the 60 block signals 20 are shown and these are arranged to protect respectively the entrance or left hand end of the two consecutive blocks C—C, and D, against trains proceeding from left to right, or in the direction of the arrow shown in block B—B. The signal 20 is shown in each case as spaced a short distance, for instance, about 500 feet on the left of the left hand end of, or in the rear of the block which it is arranged 70 to protect.

Each of the signals 20 may be of any suitable construction and may be of either of the two - position or of the three - position type. The signal illustrated is of the three- 75 position type, being provided with a semaphore 21 which is pivoted to swing from the horizontal "danger" position, shown in full lines in the signal upon the left of the drawing, into either an oblique "warning" position, or a vertical "safety" position (as shown in dotted lines in the same signal). Each signal 20 is arranged to be controlled by a track circuit which may be either of the normally open type or of the normally 80 closed type. In the form shown, each signal 20 is controlled by a normally closed track circuit including two wires 25 and 26, which connect the signal to the nearer pair of block signal rail sections (for instance 5—9 and 90 6—10) of the corresponding block, and these sections are normally supplied with electric current by a track battery 27, the terminals of which are preferably connected to the other pair of block signal rail sections (for 95 instance 11—7 and 12—8) respectively, of the same block.

To coöperate with the train stopping sections 9—11, and 10—12, of each block, each signal 20 is in a partial electric circuit including a wire 30 extending from the semaphore 21 to one of the pair of train stopping rail sections of the block preceding that protected by the signal, and a wire 31 extending from a contact plate 32 provided on the signal to either one of the adjoining block signal rail sections. A brush 33 is carried by the semaphore 21 and is arranged to engage the contact plate 32 when the semaphore 21 is in a vertical or "safety" po- 110

sition (as shown in full lines in the lower right hand portion of the drawing), or "caution" position or at 45° as shown in dotted lines in the drawing. When in either of these positions the semaphore operates to close the electrical connection between the corresponding train stopping rail section and the block signal rail section through the wire 30, semaphore 21, brush 33, contact plate 32 and wire 31. When the semaphore 21 is in the horizontal position (shown in full lines in the lower left hand portion of the drawing), the brush 33 is out of engagement with the contact plate 32, and the electrical connection between the rail train stopping section and the corresponding block signal rail sections is broken.

For automatically applying the air brake on a train and closing the throttle of the locomotive or engine, the locomotive or engine 35 of each train is provided with pneumatic apparatus which is controlled by an electro-magnet 36 carried by the locomotive. One terminal of the electro-magnet 36 is connected by a wire 37 to one terminal of a battery 38, or other source of electric energy preferably carried by the truck 42 of the tender of the locomotive, and the other terminal of the electro-magnet 36 is connected by a wire 39 to the frame of the locomotive, and is connected through the frame and wheels 40 of the locomotive to the rails 1 and 2. The other terminal of the battery 38 is connected by a wire 41 to the truck 42 of the tender of the engine, and is connected through the wheels 43 of the truck to the rails 1 and 2. The truck 42 is insulated from the other parts of the tender and from the locomotive in any suitable manner.

The pneumatic apparatus upon the locomotive includes a tank 45, which is kept filled with compressed air. This tank 45 communicates through a reducing valve 46 and a pipe 46 with the interior of a valve casing 47 through an inlet opening 48, provided in the casing. This casing is provided with an outlet 49, from which a pipe 50 leads to the lower end of a vertical cylinder 51 rigidly secured to the locomotive and provided with a vertically reciprocating piston 52 rigidly secured to the lower end of a vertical piston rod 53, upon the upper end of which is secured a valve 57 (referred to hereinafter as the air valve) which controls a corresponding port 58 in a valve casing 59. This latter valve casing 59 communicates at one end with one end of an inlet pipe 60, the other end of which communicates with a pipe section 61 which is carried by the locomotive and which is kept supplied with air under pressure by the usual or any suitable means (not shown). The latter pipe section 61 is connected in any well known or suitable manner to control air brakes (not shown) on the locomotive, and is connected

through a flexible pipe 62, a coupling 63 and a flexible pipe 64 to a pipe section 65 carried by the tender of the locomotive, and which is adapted to be connected in a well known manner to control air brakes upon the tender and upon any number of cars attached to the tender.

The train pipe coupling 63 is made in two parts, which may be readily disconnected along a central transverse line 66, and the wire 37 leading from the train battery 38, is separated at the coupling 63, and has its two adjacent ends 67 secured to the two parts of the coupling respectively, so that the tender may be conveniently disconnected from the engine without breaking the wire 37, it being understood that when the tender is connected to the engine through the coupling 63, the battery 38 is electrically connected to the truck 42 through the wire 41 and coupling 63, but when the two parts of the coupling are disconnected, the electrical connection between the battery 38 and the magnet 36 is broken.

The locomotive is provided with the usual or any suitable throttle valve 70, arranged to control a main steam pipe 71 leading from the boiler 72 to the actuating mechanism of the locomotive. This throttle valve 70 is controlled by a vertically reciprocating valve stem 73, which is arranged to be reciprocated by a bell crank lever 74, arranged to oscillate about a fixed horizontal axis on a pivot 75, an upper end of which cooperates with the valve stem 73, and the lower end of which is connected in any well known or suitable manner, as for instance, by a jointed rod 77 to a controlling lever 80, which is pivoted to swing about a fixed horizontal axis on a pivot 81. This controlling lever 105 80 extends upwardly from its pivot 81 and is provided at its upper end with a handle 82, and with a bell crank lever 83 pivotally secured thereto, and the upper end of which is normally pressed outwardly as by a spring 110 84, and the lower end of which is connected to the upper end of a rod 85 which engages at its lower end in a fixed, toothed sector 86 for holding the controlling lever 80 in a predetermined position.

For automatically actuating the controlling lever 80 to close the throttle valve 70, a bell crank lever 87 is pivotally connected to the free end of the controlling lever 80. The upper end of this bell crank lever 120 87 is provided with a yoke 88, pivotally connected thereto which surrounds and engages the spring pressed lever 83, and the lower end of the bell crank lever 87 suitably connected to the outer end of a horizontal piston rod 89, the inner end of which is rigidly secured to a piston 90, arranged to reciprocate in a horizontal cylinder 91, which is rigidly secured to the boiler 72.

For moving the piston 90 inwardly to 130

close the throttle 70, an outlet pipe 92 leads from the valve case 59 to an inlet 93 provided in the cylinder 91 outside of the piston 90. The cylinder 91 is provided adjacent its inner end with a plurality of outlets 94 arranged so that when the piston 90 is in its innermost position the outlets 94 will be in communication with the inlet 93 through the space in the cylinder 91 outside of the piston, 5 to permit the air to flow from the inlet 93 through the outlets 94.

Surrounded by the electro-magnet 36 and coaxial therewith is a vertically reciprocatory core 100 secured to the lower end of 10 which is an armature 101 arranged to be controlled by the magnet 36. Secured in the upper end of the core 100 and coaxial therewith is a valve stem 102 which carries a downwardly facing conical valve 103 arranged to coöperate with a corresponding valve seat to control the flow of air between the inlet 48 and the outlet 49. A spiral spring 105 surrounds the upper portion of the valve stem 102 and normally tends to 15 press the valve 103 into engagement with its seat. The upper end of the core 100 is conical in shape and forms a valve 106 arranged to coöperate with the corresponding valve seat 107 and to control communication 20 between the inlet 48 and a discharge opening 108, provided in the casing 47 and below the lower valve seat 107 and communicating alternately with the inlet 48 and with the outlet 49 through an annular passage 25 109 surrounding the valve stem 102. When the circuit is closed through the electric magnet 36 and the core 100 is in its uppermost position, the upper valve 103 permits communication between the inlet 48 and the 30 outlet 49, and the lower valve 106 prevents a discharge of the air through the discharge opening 108, but when the circuit through the electro-magnet 36 is broken and the core 100 has moved downwardly into its lowermost position under the action of the air pressure assisted by gravity and the spring 105, the upper valve 103 is closed, thus preventing communication between the inlet 48 and the outlet 49, and the lower valve 106 is 35 open, thus establishing communication from the outlet 49 through the discharge opening.

In the operation of this improved system, when a train enters any block the track battery 27 which is connected to that block will 40 be short-circuited by the train and the wires 25 and 26 connecting that block to its signal 20 will be deenergized, thus permitting the semaphore 21 of that signal to fall from a normally "safety" position or to remain in a 45 normally "danger" position depending upon the system employed. When the signal 20 of any given block is thus set at "danger," a second train in an adjacent block and approaching the given block, going from left 50 to right, will be stopped when it reaches

such a position that the insulated truck 42 of the tender rests upon, and the engine 35 is spaced from the train stopping rail sections 9-11 and 10-12. For instance, when the signal 20 (shown upon the left of the drawing) which protects the block C-C (shown upon the right) is set at "danger" (as indicated in full lines), a train going from left to right in the adjoining block B-B will be stopped when it reaches the position in 75 which the engine truck 40 reaches the train stopping rail sections 9-11 and 10-12 and the tender insulated truck 42 is in the preceding main track section. When the train reaches this point the circuit, which is at 80 other times normally closed from the truck 42 through the wire 41, battery 38, electro-magnet 36, wire 39, engine 40, and block signal track sections 3-9 and 4-10, or 11-5 and 12-6, is broken by the semaphore 21, 85 which breaks the connection between the train stopping section 10-12 and the block singal section 12-6.

When, in the absence of a train in the block C-C at the right, the semaphore 21 90 is set either in the inclined "warning" position or in the vertical "safety" position shown in dotted lines, the stopping section 10-12 is electrically connected to the block signal section 12-6 and consequently when 95 the insulated truck 42 is in the position shown, there would be no breaking of the circuit of the electro-magnet 36, and consequently the train would be permitted to proceed.

Normally the circuit of the electro-magnet 36 is closed, thus holding the core 100 in its uppermost position, and permitting a flow of compressed air from the supply tank 45 through the pipe 46, inlet 48, outlet 49, pipe 105 50, and into the vertical cylinder 51, thus holding the vertically reciprocatory piston 52 in its uppermost position and maintain the air valve 57 closed and preventing a flow of air from the pipe 60 through the 110 valve case 59 and pipe 92 for closing the throttle 70, the discharge opening 108 being meanwhile kept closed by the valve 106 on the core 100.

When, however, the circuit through the 115 electro-magnet 36 is broken, as hereinbefore described, the core 100 is moved into its lowermost position and prevents communication between the inlet 48 and the outlet 49 of the valve casing 47 by the closing of 120 the valve 103, but permits communication between the outlet 49 and the discharge opening 108, whereupon air is permitted to exhaust from the vertical cylinder 51 and the air valve 57 is forced downwardly under 125 the pressure of the air in the pipe 60, thus permitting the air to pass through the cas- 59 and pipe 92 and into the horizontal cylinder 91, to move the horizontally re- 130 ciprocatory piston 90 inwardly to close the

throttle valve 70 and to open the exhaust outlets 94. The opening of the outlets 94 permits the escape of air from the pipe 60 and consequently from the train pipe 61, and thus applying the air brakes to stop the train. When the air valve 57 is opened, the air is also permitted to pass downwardly through an annular passage 115 and into the upper end of the vertical cylinder 51 to press the piston 52 downwardly.

It is to be noted that in this construction the air valve 57, controlling the throttle and the air brakes, is normally held closed against the pressure in the train pipe 61 by a normally closed electric circuit, including the train battery 38 and the electromagnet 36. The breaking of the electromagnet circuit permits the air valve 57 to be opened under the pressure of the train pipe 61 to close the throttle and to apply the air brakes.

By having the train battery 38 on the truck or very near the truck, the arrangement of wiring is such that if the wire 37 between the battery and the magnet 36 should become accidentally grounded the magnet 36 would be deenergized and as a result the train would be stopped as hereinbefore described.

It is to be understood, however, that this invention is not limited to the specific construction and arrangement hereinbefore described, as it is evident that instead of having the electro-magnet 36 in a normally closed track circuit, it might be arranged in a normally open track circuit, which could be closed by the signal 20 when the signal is in a "danger" position, which would be the reverse of the system illustrated. It is also evident that the air valve 57 instead of being normally held closed against the pressure of the train pipe 61 might be arranged to be normally held closed by the pressure in the train pipe 61, and to be opened by an admission of air pressure in a cylinder corresponding to the larger cylinder 51. It is considered that these, and other changes, might be made in applying this invention, without departing from the spirit of the invention or the scope of the appended claims.

Having thus described my invention, I claim and desire to protect by Letters Patent of the United States:

1. In an automatic train stopping system, the combination with a block controlled primary track circuit including a plurality of main block sections, a train stopping section in each block formed by insulating a portion

of each of the rails of the track from the main block sections, said main block sections being electrically connected together consecutively, a train having a truck insulated from the rest of the train, a normally closed electric circuit carried by the train having one of its terminals connected to the wheels of the insulated truck and the other terminal connected to another set of wheels on the train, a train braking mechanism carried by the train normally held inoperative by said closed circuit, a single partial electric circuit for each train stopping section having one terminal connected to one of the rails of said main block sections and the other terminal connected to the corresponding rail of the train stopping section on the same side of the track, and a switch in said single partial circuit adapted to be opened or closed by the primary circuit of the next preceding block.

2. In a block signal and stopping system a plurality of main track sections electrically connected together and a train stopping rail section formed by insulating a section of each of the two rails forming the track from the adjacent main track sections, a block controlled main track circuit including the rails of said main track section, a single partial circuit for each train stopping section having one terminal connected to one rail of the main track sections and the other terminal connected to the corresponding rail of the train stopping sections, a switch in said single partial circuit adapted to be controlled by the track circuit of a preceding block.

3. In a train stopping mechanism, the combination of a train pipe detachably connected at adjacent units of the train pipe, an air brake valve and automatic means for controlling the operation of said valve comprising an electromagnet and a circuit therefor carried by the train, one terminal of which is connected to one unit of the train and the other to an adjacent unit thereof which is insulated therefrom, one branch of said circuit being connected through said detachable train pipe connections whereby when the units of the train are connected and disconnected the electrical connections for the circuit are automatically made and broken.

In witness whereof I have hereunto set my hand this 30th day of July, A. D. 1915.

FRANK C. WILLIAMS.
